United States Patent Office

Des. 226,103
Patented Jan. 23, 1973

226,103

COMBINED ROLLER COASTER AND VEHICLE THEREFOR

James Smith and Laurie J. Campbell, Erie, Pa., assignors
to Louis Marx & Co., Inc.

Filed Apr. 12, 1971, Ser. No. 133,099

Term of patent 14 years

Int. Cl. D21—03

U.S. Cl. D34—5

FIG. 1 is a front perspective view of a combined roller coaster and vehicle therefor showing our new design;

FIG. 2 is a front perspective view of FIG. 1 with the vehicle omitted for clarity of illustration;

FIG. 3 is a rear perspective view of FIG. 2;

FIG. 4 is a left side elevational view of FIG. 1;

FIG. 5 is a bottom plan view of the vehicle only;

FIG. 6 is a bottom perspective view of FIG. 5.

We claim:

The ornamental design for a combined roller coaster and vehicle therefor, as shown and described.
